UNITED STATES PATENT OFFICE.

EDMUND MORRIS, OF MICHIGAN CITY, INDIANA.

DESIGN FOR CANE FABRIC.

SPECIFICATION forming part of Design No. 25,841, dated March 31, 1896.

Application filed December 30, 1895. Serial No. 579,827. Term of patent 7 years.

to all whom it may concern:

Be it known that I, EDMUND MORRIS, a citizen of the United States, residing at Michigan City, in the county of La Porte and State of Indiana, have invented and produced a new and original Design for Cane Fabric, of which the following is a specification, reference being had to the accompanying drawing, forming part hereof, which shows a piece of cane fabric with my design applied.

My design consists of the diagonal stripes crossing each other in the body of the fabric, forming a plaid, and each stripe containing and presenting to the eye of the ordinary observer a number of star-shaped figures arranged between octagonal figures.

The accompanying drawing shows a facsimile of a piece of cane fabric with my design applied.

A indicates one set of diagonal stripes; B, set of parallel stripes intervening between the stripes A; C, another set of diagonal stripes corresponding with the stripes A, but

arranged at right angles thereto, and D indicates a set of stripes intervening between the stripes C. All of the stripes contain octagonal figures a, and the stripes B and D contain star-shaped figures, which are prominent at the squares where the stripes B and D cross each other. There is in these stripes a four-pointed star-shaped figure between each group of four octagonal figures.

The leading feature of my design is the arrangement of diagonal stripes forming a plaid and containing a number of star-shaped figures and octagonal figures.

I claim—

The design for cane fabric substantially as herein shown and described.

In testimony whereof I have hereunto subscribed my name.

EDMUND MORRIS.
